DESIGN FOR AN URN UNIT FOR CREMATED REMAINS

William H. Warren, San Francisco, Calif.

Application November 9, 1946, Serial No. 134,677

Term of patent 14 years

(Cl. D19—1)

To all whom it may concern:

Be it known that I, William H. Warren, a citizen of the United States of America, residing at San Francisco, in the county of San Francisco and State of California, have invented a new, original, and ornamental Design for an Urn Unit for Cremated Remains, of which the following is a specification, reference being had to the accompanying drawing, forming a part thereof.

The figure is a perspective view of an urn unit for cremated remains showing my new design.

I claim:

The ornamental design for an urn unit for cremated remains, substantially as shown.

WILLIAM H. WARREN.
